UNITED STATES PATENT OFFICE.

CARL STREIT, OF BROOKLYN, NEW YORK, ASSIGNOR TO STREIT RADIO CORPORATION,
OF NEW YORK, N. Y., A CORPORATION OF NEW YORK.

DESIGN FOR A RADIOCABINET.

Application filed November 28, 1925. Serial No. 15,569. Term of patent 3½ years.

To all whom it may concern:

Be it known that I, CARL STREIT, a citizen of the United States, residing in the borough of Brooklyn, county of Kings, city and State of New York, have invented a new, original, and ornamental Design for Radiocabinets, of which the following is a specification, reference being had to the ac-

companying drawing, forming part thereof.

The figure is a front elevation of a radiocabinet, showing my new design.

I claim:

The ornamental design for a radiocabinet, as shown.

CARL STREIT.
